US00D976831S

(12) **United States Design Patent** (10) **Patent No.:** **US D976,831 S**
(45) **Date of Patent:** **** Jan. 31, 2023**

(54) **FUEL CELL**

- (71) Applicant: **Cummins Enterprise LLC**,
Indianapolis, IN (US)
- (72) Inventor: **Darren Bawden Hickey**, Halfmoon,
NY (US)
- (73) Assignee: **CUMMINS ENTERPRISE LLC**,
Indianapolis, IN (US)
- (**) Term: **15 Years**
- (21) Appl. No.: **29/745,527**
- (22) Filed: **Aug. 6, 2020**

Related U.S. Application Data

- (62) Division of application No. 29/680,016, filed on Feb. 12, 2019, now Pat. No. Des. 894,124, which is a division of application No. 29/580,094, filed on Oct. 5, 2016, now Pat. No. Des. 844,562.

Primary Examiner — Catherine Ho

(74) *Attorney, Agent, or Firm* — Barnes & Thornburg LLP

(57) **CLAIM**

The ornamental design for a fuel cell, as shown and described.

DESCRIPTION

FIG. 1 is a perspective view of a fuel cell, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken line portion of the figure drawings is included to show portions of the article that form no part of the claimed design.

1 Claim, 4 Drawing Sheets
